UNITED STATES PATENT OFFICE

2,408,101

ELECTROLYTIC PRODUCTION OF
PINACOLSOber C. Slotterbeck, Rahway, N. J., assignor to
Standard Oil Development Company, a corpora-
tion of Delaware

Application July 11, 1942, Serial No. 450,519

6 Claims. (Cl. 204—77)

1

The present invention pertains to a method of preparing vicinal glycols by electrolytic reduction of ketones and generally to all types of carbon to carbon reductive condensation reactions.

Specifically, this invention is concerned with the reduction of acetone electrolytically to tetramethylethylene glycol.

It is the object of the present invention to provide the art with a novel and highly advantageous method of electrolytically forming vicinal glycols and especially pinacol from the corresponding ketone, and also to provide the art with novel electrodes for effecting the reduction of organic compounds.

The electrolytic reduction of ketones can take place at the cathode surface according to any one of the following reactions:

Other side reactions result in the formation of metal alkyls, especially when the reduction is effected in acid medium with lead cathodes.

An electrolytic method for effecting the reductive condensation reaction whereby acetone is converted to pinacol using a lead cathode and an acid catholyte is described in German Patent 113,719 (1899).

Several German patents pertaining to the electrolytic reduction of acetone to pinacol were issued in the period 1912-1920. Among these were D. R. P. 306,304 (1917), 306,523 (1918) and 324,919 (1920). The principal developments made in this period appear to have been the use of mixed metal and alloy cathodes, such as 4 to 10% copper-96 to 90% lead mixtures and 10% tin-90% lead alloy, and the use of horizontally suspended cathodes to prevent the metal alkyls formed from accumulating on and decreasing the activity of the electrode surface.

All of the prior processes for electrolytically converting acetone to tetramethylethylene glycol have been unsatisfactory either because pinacol current efficiency or the overall current efficiency or both were too low.

It has now been found that the formation of

2

toxic lead alkyls which diminish the effectiveness of the cathode can be minimized and the reduction of ketones to vicinal glycols effected with good current efficiency and high ratio of glycols to other reduction products by utilizing as the cathode sheets of copper or other metal of low hydrogen overvoltage coated with zirconium. In contrast to lead, which tends to form insoluble lead alkyls during the electrolysis, which alkyls coat the cathode and rapidly diminish the effectiveness of the cathode, the zirconium coating on the cathode forms zirconyl sulfate which is soluble in the catholyte and therefore does not coat or impair the efficiency of the cathode. The zirconium coating can be easily applied to the low hydrogen overvoltage metal by electrolysis.

Deposits of metallic zirconium were obtained from an aqueous complex sulfate bath substantially in accordance with the conditions described by Brandt and Linford, Trans. Electrochem. Soc. 70, 431 (1936). The conditions used by applicant were as follows:

25 Anode: Platinum sheet.
Cathode: Buffed and cleaned copper sheet.
Electrolyte: Produced by converting 18.0 g. of ZrO_2 to the sulfate, dissolving in 100 cc. of 0.5 M. Na_2SO_4 solution and diluting to 500 cc.
30 Current density: 0.12-0.2 amp./cm.²
Temperature: 20° C.
Total current passed: One ampere-hour.

It is preferred to apply a zirconium coating to the low hydrogen overvoltage metal base in such thickness that it weighs from about 0.01 to about 0.5 g./sq. dm.

The ketones which may be treated in accordance with the present invention correspond to the general formula

45 wherein the R's stand for a member of the group consisting of alkyl and aryl radicals and alkyl and aryl radicals substituted by a group which is not reducible under the conditions employed, i. e., halogen, carboxyl, etc. Such ketones include, for example acetone, methyl ethyl ketone, diethyl ketone, methyl propyl ketone, ethyl propyl ketone, acetophenone and benzophenone.

By using mixtures of different ketones, it is possible to prepare certain mixed glycols. For example, acetone may be condensed with methyl

ethyl ketone to form the glycol corresponding to the formula

or methyl ethyl ketone may be condensed for example with acetophenone to form the glycol

The glycols formed in accordance with the present invention correspond to the general formula

wherein each R stands for an alkyl or aryl radical or an alkyl or aryl radical substituted by a substituent such as halogen, carboxyl, etc.

A cell suitable for carrying out the reduction of ketones in accordance with the present invention is shown diagrammatically in the accompanying drawing.

Fig. 1 is a plan view, partly in section, of a single unit cell, and

Fig. 2 is an isometric view of the cathode of the present invention with part of the coating removed.

The single unit cell shown consists of a rectangular jar or the like b arranged in a cooling bath a. An anode e of lead or the like is arranged inside an acid resistant diaphragm d which diaphragm divides the cell into an anode and cathode compartment. As shown, 2 cathodes c having a zirconium coating thereon are arranged in the cell.

The details of the cell are not critical to my invention and the cell may be altered in numerous ways. For example, a number of cells could be combined in a single tank and if desired the process could be carried out continuously by providing a circulating pump, an overflow means for drawing off the catholyte from the cell, means for separating electrolysis products from the withdrawn catholyte and means for making the catholyte up to initial strength for reintroduction into the cell.

Fig. 2 illustrating the electrode in accordance with the present invention has part of the zirconium coating removed to show the base.

The use of a diaphragm is recommended since the products formed at the cathode are liable to be oxidized at the anode. The use of a diaphragm may be avoided if desired however by the use of anolyte and catholyte of unequal densities, in cells provided with horizontal electrodes, the use of a high anodic current density or by the use of anodes having a low oxygen overvoltage, i. e., nickel or by a combination of two or more of these expedients.

Aside from the nature of the cathode surface, the factor which has the greatest effect upon the course of the reaction in the cell is the concentration and type of electrolyte used. Acid media have given the best results. The ratio of ketone to water in the catholyte should be high. However, a ratio of 4/1 appears to be approximately the upper limit economically because of the high resistivity of the solution which would greatly increase the power cost. In the production of pinacol the preferred catholyte is one containing about 4 volumes of acetone for each volume of sul-

furic acid of about 20% strength. The acid, however, may vary in strength between about 15% and about 40%. The acid strength indicated is percentage by weight.

5 The anolyte may be a sulfuric acid solution of about 15 to 40% strength. The electrolyte is preferably maintained at temperatures between about 0° C. and about 25° C. The current density applied may vary between about 0.1 and about 10 4.0 amperes/sq. dm., the preferred current density being within the range of about 1 to about 2 amperes/sq. dm.

15 The following example serves to illustrate my invention but it is to be understood that my invention is not limited thereto.

Example 1

3 1/2 liters of a 4/1 acetone-20% sulfuric acid solution were placed in the cathode compartment of a cell as shown in the drawing. The anolyte used was 25-40% sulfuric acid and the anode was lead. The cathodes used are copper sheets onto which zirconium was electroplated from an aqueous solution of zirconyl sulfate and sodium sulfate as described above.

25 Electrolysis was effected at about 10° C. at a current density of 1.0 amperes/sq. dm. and at 6-8 volts. The run was continued for 3 hours and a total of 24 ampere hours were supplied to the cell. Upon conclusion of the electrolysis the catholyte was stripped of isopropyl alcohol and unreacted acetone and pinacol (tetramethylethylene glycol) was separated as the hexahydrate by cooling and filtering the stripped catholyte. 24.8 grams of pinacol hydrate and 2 grams of isopropyl alcohol were obtained corresponding to a current efficiency based upon pinacol of 24%. The ratio of pinacol hydrate to isopropyl alcohol was 12.4/1. There was no metal alkyl formation on the cathode.

40 What I claim and desire to secure by Letters Patent is:

1. In the process of producing glycols corresponding to the general formula

45 wherein R stands for a member of the group consisting of alkyl and aryl radicals and substituted alkyl and aryl radicals by the electrolytic reduction of an aqueous acid solution of a ketone of the formula

50 wherein R stands for a member of the group consisting of alkyl and aryl radicals and alkyl and aryl radicals substituted by a group which is not reducible under the reaction conditions, the improvement which comprises effecting the said reduction at a cathode consisting of copper coated with zirconium.

55 2. The process of producing tetramethylethylene glycol which comprises subjecting a solution of acetone in an aqueous acid solution containing about 15 to 40 wt. per cent of sulfuric acid to electrolytic reduction at a current density of between about 0.1 and 4 amperes per sq. dm. at a temperature between about 0° C. and about 25° C. in contact with a cathode consisting of copper coated with zirconium.

60 3. The process of producing tetramethylethylene glycol which comprises subjecting a solution

of about 4 parts by volume of acetone in 1 part by volume of an aqueous solution of sulfuric acid of about 20 wt. per cent strength to electrolytic reduction at a current density of between about 1 and 2 amperes per sq. dm.; in a diaphragm cell at a temperature between about 0° and 25° C. in contact with a cathode of copper coated with zirconium.

4. The process as defined in claim 1 wherein

the zirconium coating on the cathode weighs about 0.01 to about 0.5 g./sq. dm.

5. The process as defined in claim 2 wherein the zirconium coating on the cathode weighs about 0.01 to about 0.5 g./sq. dm.

6. The process as defined in claim 3 wherein the zirconium coating on the cathode weighs about 0.01 to about 0.5 g./sq. dm.

OBERT C. SLOTTERBECK.
